NORWOOD PENROSE, OF PHILADELPHIA, PENNSYLVANIA.

Letters Patent No. 66,624, dated July 9, 1867.

IMPROVED SELF-BAILING SURF AND LIFE-BOAT.

The Schedule referred to in these Letters Patent and making part of the same.

TO ALL WHOM IT MAY CONCERN:

Be it known that I, NORWOOD PENROSE, of the city of Philadelphia, in the State of Pennsylvania, have invented a new and useful improvement in Self-Bailing Surf and Life-Boats; and I do hereby declare that the following is a full, clear, and exact description of the construction and operation of the same, reference being had to the accompanying drawings, making a part of this specification, in which an "amidships" section only of the said improved boat is shown—

Figure 1 being a vertical longitudinal section on the dotted line *x* of fig. 3.

Figure 2, a vertical transverse section on the dotted line *y* of the same figure; and

Figure 3, a plane view of the upper or floor side of the said "amidships" section of the boat—

Like letters of reference indicating the same parts when in the different figures.

The two "ends" of the boat are intended to be elevated in the usual manner required in a self-righting life-boat, and also the whole length of the boat between the said ends partitioned both longitudinally and transversely, so as to divide it into several water-tight compartments; and each of which, as well as the ends, to contain an accurately fitting air-tight elastic case, substantially in the same manner and for the same purposes as will hereinafter be explained in describing the "amidships" section shown in the drawings.

The object of my invention is to cause the boat to relieve herself of shipped water in a more perfect and rapid manner than heretofore, and to provide against the boat's becoming "water-logged" in case of leaks in the compartments, or in case of any of them becoming "stove" in launching or in boarding a wreck, &c.

My invention consists in providing a "well" or trunk, say about one-fourth of the length of "overall," running fore and aft, amidships, and vertically down through the floor, which is above the water line, and also through the keel, in combination with any suitable self-acting valve or valves opening downward in its upper end so as to allow the water which may be shipped to run rapidly and freely down through the same, and prevent its return, substantially as hereinafter described.

My invention also consists in providing one or more similar trunks extending obliquely downward through both the starboard and larboard sides of the floor, respectively, and opening at a point just above the keelson, into a well or trunk opening down through the keel, and also having self-acting valves at their upper ends, opening downward, substantially as in the "amidships" well before mentioned.

And my invention also consists in providing each separate compartment of the boat with an interior air-tight elastic case, conforming to the respective compartments, substantially as hereinafter described and set forth.

Referring to the drawings, A is the amidships well or trunk, and *a' a'* the valves thereof; B B' the oblique trunks, communicating with A, and *b'' b'' b''' b'''* the valves thereof; C C are the compartments into which the boat is divided, and D D the elastic air-tight cases within the compartments. The well or trunk A is similar in construction, arrangement, and location to the well-known "centre-board well." It is a vertical opening in the middle of the boat, extending down through the floor and keel in a water-tight manner, and is about one-fourth of the length "overall." (See figs. 1 and 2.) Its upper end is provided with any suitable self-acting valve or valves, *a' a'*. In this case the valves are suspended from a round bar, 2, on which they tilt downward, as indicated by the dotted lines in fig. 2, by the pressure of any water that may be on the floor E of the boat, thus allowing the water to pass freely and rapidly down into the well A, and immediately afterward closing and preventing any discharge of water upon the floor E from below by surging up through the well A during the pitching or rolling of the boat in a heavy surf. The upper ends of the oblique trunks B B' open, respectively, through the starboard and larboard sides of the floor E, and, extending obliquely downward, their lower ends open directly into the amidships well A, at points a little above the keelson. (See figs. 1 and 2.) Their upper ends are provided with self-acting valves *b'' b'''*, operating in the same manner and for the same purposes as those in the well A.

The keel is intended to be made of metal, and therefore heavier than is usual in surf and life-boats. The trunk which forms the well A passes from the floor or deck E vertically downward through the keelson and the keel, and therefore opens along in the middle of the latter, and affords an ample and ready outlet for all the water that may be shipped, without in the least interfering with or impairing the stiffness and strength of the

bottom of the boat, or subjecting the said trunk or well to be either choked up or damaged in running the boat aground.

The elastic air-containing cases D D are each made of flat plates, say a quarter or three-eighths of an inch thick, more or less, of vulcanized gum-elastic, cut to correspond with the forms of the inner boundaries of the sides and ends of the respective bulk-heads and compartments of the boat, and then cemented together at their edges so as to form strong, closed, air-holding elastic cases, which will fit within and be retained by the said respective bulk-heads and compartments. (See figs. 1 and 2.)

Operation.

As this improved boat has elevated, buoyant ends or air-containing bulk-heads, and several or separate air-containing compartments below the deck or floor, and also an extra strong and heavy keel, as described, she cannot become water-logged nor be easily capsized in a rough sea; and when the latter happens, the boat will right herself almost instantly, and discharge all the shipped water in less time than half a minute. She cannot lie on her beam ends on the surface of the sea, but instantly on rising falls into such a position as brings the mouth or valve end of the submerged oblique trunk B or B' higher than its outlet or point of junction with the amidships well A, and, as the water in that side of the boat becomes diminished in quantity by finding its level with the water line in running down through the said oblique trunk, the self-righting and bailing operation increases in rapidity, and ultimately brings the valved mouth of the amidships well A into a position to aid more effectively in the discharge of the whole of the water. And, should the boat spring a leak or become stove at any part, in launching, or in boarding a wreck, the elastic air-containing cases D will yield to the impact sufficiently to prevent them from being broken through thereby, and, reacting, recover their original bulk, and thus effectually prevent the boat from becoming either swamped, water-logged, or impaired in buoyancy in any appreciable degree. Besides the superior self-righting and self-bailing qualities of this boat, it will be readily seen that as the only opening for the discharge of the shipped water is confined to the keel, the bottom of the boat remains perfect, *i. e.*, it is not impaired or weakened by the cutting of openings through it for discharge-tubes or trunks, as is required in those boats which discharge through their bottoms.

I am aware that tubes connected with openings therefor in the bottom of the boat have been applied for discharging the shipped water, as in Francis' patent of July 11, 1839, and in Wadsworth's boat, rejected December 23, 1854; that air-tight compartments have been placed in the sides and on the inner bottom of a boat, as in the said Wadsworth's application; that air-chambers open at the bottom have been applied, as in Shear's patent of May 25, 1858; and that a twin or double boat, consisting of a longitudinal central ballast-chamber, arranged between two longitudinal floating air-chambers, having open vertical tubes for discharging shipped water through each of the latter, has been produced, as shown in the patent of J. R. Grace, March 6, 1860; therefore, I do not desire to claim broadly the application of air-chambers either to the ends, sides, or bottom of a boat, nor dividing the boat into separate compartments; neither do I desire to claim broadly the discharging of the shipped water through the bottom of the boat, nor the application of water-proof lining to the different compartments of a life and surf-boat; but, having fully described my improvement, and pointed out its superior utility, what I claim as new, of my invention, and desire to secure by Letters Patent, is confined to the following, *viz.*:

1. I claim, in a self-righting and bailing surf and life-boat, provided with a heavy keel and elevated buoyant ends in the usual manner, the amidships trunk or well A, in combination with a deck or floor, E, and any suitable automatic valve, *a'*, at its upper end, the said trunk or well A passing vertically downward through the keelson and the keel of the boat, substantially as described and set forth for the purpose specified.

2. I claim, in a self-righting and bailing surf and life-boat provided with a heavy keel and elevated buoyant ends in the usual manner, the oblique trunks B B', in combination with a deck or floor, E, and any suitable automatic valves at their upper ends, the said oblique trunks extending from the starboard and larboard sides, respectively, of the floor or deck, and opening into a vertical trunk or well, A, at points just above the keelson of the boat, so as to discharge their water vertically through the keel of the boat, substantially as described and set forth.

3. I also claim, in combination with a self-righting and bailing life and surf-boat, the air-containing elastic cases D, the same being constructed as described, and applied within the respective compartments and bulk-heads of the boat, as and for the purpose specified.
